UNITED STATES PATENT OFFICE.

BERT G. DUNHAM, OF HAWTHORNE, NEW JERSEY, ASSIGNOR, BY MESNE ASSIGNMENTS, TO WESTERN ELECTRIC COMPANY, INCORPORATED, A CORPORATION OF NEW YORK.

AUTOMATIC TELEPHONE-EXCHANGE SYSTEM.

1,194,367.

Specification of Letters Patent. Patented Aug. 15, 1916.

Application filed June 7, 1915. Serial No. 32,688.

To all whom it may concern:

Be it known that I, BERT G. DUNHAM, a citizen of the United States, residing at Hawthorne, in the county of Passaic and State of New Jersey, have invented certain new and useful Improvements in Automatic Telephone-Exchange Systems, of which the following is a full, clear, concise, and exact description.

10 This invention relates to telephone exchange systems wherein calling lines are associated with connecting circuits by automatic finder switches. In such systems it is very important that the time interval between the removal of the receiver from its switchhook by the calling party and the connection of the finder with his line be small. This is especially true in full automatic systems, that is, in systems wherein the selection and connector are set by a sender manipulated by the calling subscriber, since some of the impulses would be lost if transmitted before the finder had reached the calling line terminal.

25 It is the object of this invention to provide a circuit arrangement for automatic finder switches of the two-movement type, wherein this interval is reduced to a minimum.

A feature of the invention is the provision 30 of an efficient finder circuit arrangement of this type which obviates the necessity of a side switch or similar electro-mechanical control switch.

Referring to the drawing which illustrates only so much of a telephone exchange system as is necessary for a comprehension of the invention, the lines terminate as calling lines in multiple contacts 41, 42 of a number of automatic finder switches, a 40 multiple test terminal 40 being also associated with each line. The lines are divided in groups, the finder being adapted in a primary movement to pick out the group of lines containing the calling line, 45 and in a secondary movement the calling line therein. An idle finder is associated with the lines by a starter wire 22. Each finder is provided with an auxiliary switch 5, which has a contact 6 for each group of lines, these contacts being connected in multiple and being adapted to be engaged by a brush 25 carried by the finder brush shaft (not shown), during the primary movement of such shaft in search of the calling line 55 group. Each group switch 5 is also pro-

vided with a home contact 29, upon which the brush 25 normally rests. Each group of lines is also provided with a relay 17 which may be energized by any line relay 10 of the same group. This relay, when energized, 60 removes ground from its multiple contacts 6 in the finder group switches, and simultaneously grounds starter wire 22 leading to the primary stepping magnet 18 of the pre-selected finder. The primary magnet 18 65 steps the brush shaft in a primary direction until the brush 25 encounters the multiple group contact 6 of the calling line group, from which ground was removed by the energization of the corresponding group relay 17. 70 The primary movement of the brush shaft is then stopped, at which moment the finder brushes 31, 32, 33 are in operative relation to multiples of the calling line group in the finder. The secondary movement of the 75 brush shaft is then initiated, the test brush 33 in this movement wiping over the test terminals 40 of the lines in the calling group. When such test brush reaches the calling line test terminal 40 therein, it operates the cut-off relay 12 thereof which is connected to said test terminal. The cut-off relay thereupon opens the circuit of the line relay 10 which in turn, by opening the circuit of the 80 group relay 17 and removing ground from starter wire 22, causes the finder brushes to stop in connection with the calling line.

A general outline of the system having been given, the operations involved in extending a calling line will now be traced in detail.

The removal of the receiver by the subscriber at substation A energizes the line relay 10 over the following circuit: free pole 95 of battery, left winding of line relay 10, conductor 11, left armature and back contact of cutoff relay 12, line conductor 14, the telephone set at substation A, line conductor 15, inner armature and back contact of cutoff relay 12, conductor 16, right winding of line 100 relay 10, to ground. The energization of the line relay 10 closes the circuit of relay 17, common to this group of subscribers. This relay, upon its energization, closes the following circuit for the primary stepping magnet 18 to move the finder in a primary direction in search of the group of lines initiating the call: free pole of the battery, primary magnet 18, its armature and back contact, conductors 19 and 20, primary off-nor- 105 110

mal spring PON', starting conductor 22, armature and front contact of group relay 17 to ground. Relay 23 is energized in multiple with the primary stepping magnet 18 by way of conductors 24, 20, primary off-normal spring PON' to ground, over the circuit just traced. This relay 23 then locks itself to ground over the following circuit: free pole of battery, relay 23, its inner armature and front contact, conductor 28, contact brush 25, home contact 29, conductors 30, 19, 20, primary off-normal spring PON', starting conductor 22, to ground at the armature and front contact of group relay 17. Thus, the primary magnet 18 steps the brush shaft in a primary direction as long as its circuit is closed at the inner armature and front contact of relay 23, which circuit is in turn maintained closed as long as the brush 25 of the group switch S encounters contacts 6, grounded at the armatures and back contacts of the relays 17 of non-calling groups. When the contact 6 of the calling line group is reached, which is assumed to be the first, and from which ground was removed by the energization of the group relay 17, the circuit of relay 23 is opened and the deenergization of this relay opens the circuit of the primary stepping magnet 18, thus causing the primary movement of the brush shaft to be stopped with the brushes 31, 32 and 33 in operative relation to the group of lines containing the calling line whose substation is designated A.

The energization of group relay 17, upon the initiation of the call, closed the following circuit for a slow relay 38, in parallel with magnet 18 and relay 23, to prepare a circuit for secondary stepping magnet 34: free pole of battery, relay 38, conductors 36, 52, off-normal spring PON', starting conductor 22, to ground at the armature and front contact of said group relay, and after the first primary step of the finder brush shaft and the consequent transfer of off-normal spring PON' to its lower contact, this relay locks itself over the following circuit: free pole of battery, relay 38, its upper armature and front contact 37, starting conductor 22 including spring PON', armature and front contact of group relay 17 to ground. Thus the deenergization of relay 23, as brush 25 reaches the ungrounded calling group contact 6, and consequent engagement of its outer armature and back contact, immediately closes the following circuit for the secondary stepping magnet 34 to move the finder brushes 31, 32, 33 over the terminals of the selected group in search of the calling line therein: free pole of the battery, stepping magnet 34, its armature and back contact, conductor 35, outer armature and back contact of relay 23, conductor 36, upper armature and front contact 37 of relay 38, starter wire 22 including spring

PON', now closed to its bottom contact, to ground at the armature and front contact of group relay 17. The test brush 33 of the line finder, in passing over the test terminals 40, energizes in succession the cut-off relays 12 of the lines of the calling group. When the terminals 40, 41, 42 of the calling line are reached, the energization of the cutoff relay 12 thereof deenergizes the line relay 10, which, in allowing its armature to retract, opens the circuit of the group relay 17. The retraction of the armature of group relay 17 opens the circuit of the secondary stepping magnet 34, thus stopping the finder brushes 31, 32, 33, upon the terminals 41, 42, 40 of the calling line, thus extending the calling line by way of conductors 43, 44 to the stepping relays 53 of a first selector. The deenergization of the relay 17, upon the operation of the cutoff relay 12, also deenergizes relay 38.

The energization of relay 38, upon the attraction of the armature of group relay 17 when the call was initiated, closed a circuit for a relay 50 to open the connection of the battery to the brushes 31, 32 during the setting of the finder on the calling line, to prevent interference with existing connections. This circuit is as follows: free pole of battery, relay 50, conductor 51, 52, armature and front contact 53 of relay 38, starter wire 22, including spring PON' and its lower contact, armature and front contact of group relay 17 to ground.

The deenergization of relay 38, upon the finding of the line, causes the release of this relay 50, which at its armature and back contacts associates the stepping relay 53 of the first selector with conductors 43, 44. This stepping relay is adapted to be intermittently operated by the sender S at calling substation A in the well-known manner, to set the first selector in operative relation to the desired group of trunks. The trunk hunting operation then follows. Since this part of the system is not claimed herein, it is not shown in detail. It is sufficient to state that during conversation, relay 50 is locked up in a circuit controlled by the first selector, and when this selector is released, upon the breaking down of the connection, a ground is placed upon conductor 46 leading back to the finder. The grounding of conductor 46 energizes the release magnet 45 to release the finder over the following circuit: magnet 45, finder off-normal contact PON², conductor 49, lower armature and back contact of relay 38, conductor 46, to ground. The release magnet 45 then closes the circuit of relay 50. When the finder reaches its normal position the release magnet 45 becomes deenergized by the opening of spring PON², and deenergizes relay 50. Thus the connection to brushes 31, 32 is also opened during the restoration of the finder to pre-

vent interference. It will be understood that while the calling line is shown as extended to a first selector, the invention is just as applicable to a system wherein the calling line is extended to an operator's position.

What is claimed is:

1. In combination, groups of lines, finders wherein said lines terminate in multiple contacts, a starting conductor adapted to 10 preselect an idle finder, a group switch associated with each finder and having a multiple contact for each group and a brush adapted to coöperate therewith, a relay for each group adapted normally to maintain 15 ground upon its group contact, a line relay for each line adapted to energize the corresponding group relay, and primary and secondary magnets for each finder, of a circuit for said primary magnet closed upon 20 the energization of a group relay and leading through an off-normal contact of said finder, a control relay therefor energized in parallel therewith, circuits for said relay including a front contact thereof and 25 grounded contacts of non-calling groups, a circuit for said secondary magnet controlled at a back contact of said control relay, and means for opening said circuit when the calling line is reached.
- 30 2. In combination, groups of lines, finders wherein said lines terminate in multiple contacts, multiple test terminals for the lines in said finders, a starting conductor adapted to preselect an idle finder, a group switch associated with each finder and having a multiple contact for each group and a brush adapted to coöperate therewith, a relay for each group adapted normally to maintain 35 ground upon its group contact, a line relay for each line adapted to energize the corresponding group relay, and primary and secondary magnets for each finder, of a cir- 40

cuit for said primary magnet closed upon the energization of a group relay and leading through an off-normal contact of said 45 finder, a control relay therefor energized in parallel therewith, circuits for said relay including a front contact thereof and grounded contacts of non-calling groups, a circuit for said secondary magnet controlled 50 at a back contact of said control relay and a front contact of said group relay, and a cutoff relay for each line connected to the test terminal of said line in the finder and adapted to be operated when the calling 55 line is reached to deenergize the line relay to cause the group relay to open the secondary stepping circuit.

3. The combination with an automatic switch, primary and secondary magnets 60 therefor, a control relay, a circuit for energizing said primary magnet and said relay simultaneously, a circuit for continuing the operation of said magnet including an armature and front contact of said relay, and 65 an operating circuit for said secondary magnet including an armature and back contact of said relay.

4. The combination with an automatic switch, primary and secondary stepping 70 magnets therefor, a control relay, a circuit for energizing said primary magnet and said relay simultaneously, a circuit for maintaining the energization of said control relay, and a stepping circuit for continuing 75 the operation of said primary magnet including an armature and front contact of said relay, and a stepping circuit for said secondary magnet including an armature 80 and back contact of said relay.

In witness whereof, I hereunto subscribe my name this 3rd day of June, A. D. 1915.

BERT G. DUNHAM.
